UNITED STATES PATENT OFFICE.

JOHN MARCUS STUART, OF ABILENE, TEXAS.

COTTON CLEANER.

Application filed June 25, 1927. Serial No. 201,503.

This invention relates to cotton cleaners and it is an object of the invention to provide a cleaner of this kind which operates to evenly distribute the cotton over a cleaning element.

It is also an object of the invention to provide a device of this kind comprising a series of horizontally disposed rollers operating to spread the cotton delivered thereto into a relatively thin bat together with a vertical series of rollers to which such bat is delivered and caused to travel in a downward and upward direction together with a cleaning element coacting with such bat in both its downward and upward travel.

The invention consists in the details of construction and in the combination and arrangement of the several parts of my improved cotton cleaner whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a vertical sectional view and of somewhat a diagrammatic character illustrating a cotton cleaner constructed in accordance with an embodiment of my invention, certain of the parts being shown in elevation;

Figure 2 is a view in top plan with portions broken away of the structure illustrated in Figure 1.

As disclosed in the accompanying drawings, my improved cleaner comprises an upper horizontally disposed housing 1 having a permanent top 2 and a removable top 3 coacting with the remaining portion of the housing 1, thus providing means whereby ready access may be had within the housing 1.

In communication with the housing 1 through the permanent top 2 is a separator S of a conventional type which is interposed in the flue conveyor 4 leading from a wagon, cotton house or other source of supply.

The communication between the separator S and the housing 1 is through a tubular member 5 which may be termed a hopper. Mounted in the hopper 5 is a swinging valve 6 operated by a throw lever 7 whereby the

cotton may be directed upon a spiked drum 8 or to the spiked carry-off belt 9 the upper stretch of which travels through the lower portion of an internal hopper or well 10 provided in the housing 1 and outwardly of and immediately adjacent to the drum 8.

The drum 8 hereinbefore referred to constitutes an end drum of a horizontally disposed series of drums arranged within the upper portion of the housing 1 with adjacent drums in gear connection, as at 11, whereby said drums will be caused to rotate in unison and in the same general direction. The end drum 8 hereinbefore referred to also has operatively connected therewith a pulley 12 or the like adapted to be coupled to a suitable source of power.

The second or opposite end drum 8 is arranged above a vertically disposed series of spiked drums 8', said end drum 8 and the drums 8' being also in suitable gear connection for corresponding simultaneous rotation.

The series of drums 8' extend downwardly within a depending housing 14 the upper portion of which is in communication with the end portion of the housing 1 remote from the hopper or well 10. The outer wall of the housing 14 is provided with a removable door or panel 15 to permit ready access within the housing 14 and which is particularly desirable in the event of choking within said housing 14. The inner face of the housing 14 is provided with the doors 16 also permitting access within such housing and especially to relieve choking therein.

Underlying the upper series of drums 8 is a cleaning screen 17 leading from the upper portion of the hopper or well 10 to a point substantially midway between the two outer drums 8 remote from said hopper or well 10. This cleaning screen 17 below each of the superimposed drums 8 is substantially concave to conform to the periphery of the drum.

The outer end of the screen 17, or that end portion of the screen remote from the hopper or well 10, is continued by a depending cleaning screen 18 interposed between the drums 8' and the inner wall of the housing 14. This screen 18 extends below the lowermost drum 8' and continues upwardly of the cleaning screen 19 arranged between the outer wall of the housing 14 and the drums 8' to the top of the housing

1. These cleaning screens 18 and 19 adjacent to each of the drums 8' are curved or formed to closely approximate the peripheries of said drums.
- 5 Within the lower portion of the housing 14 and below the drums 8' is arranged a hopper 20 which receives dirt, trash or the like separated from the cotton during a cleaning operation and this hopper 20 discharges into a conveyor 21 for carrying off such dirt, trash or the like. The conveyor 21, as herein disclosed, is of a spiral type and delivers to a flue 22 which may be in communication with a suitable suction fan.
- 15 Supported below the cleaning screen 17 is a hopper 23 to receive dirt, trash or the like passing through said screen 17 and such dirt or the like is carried by a conveyor 24, herein disclosed as of a spiral type, to a carry-off spout 25 which discharges into the upper portion of the housing 14.
- 25 As indicated by the arrows in Figure 1, the drums 8 rotate upwardly and in a direction away from the hopper or well 10 and with the valve 6 properly set, as indicated by full lines in Figure 1, the cotton as delivered within the housing 1 is carried by the drums 8 over the tops thereof resulting in an effective spreading of the cotton into a 35 bat-like formation and as such spreaded or bat cotton passes downwardly of the drums 8', the resultant action thereon in connection with the cleaning screen 19 will effect a separation of dirt, trash or the like in the cotton and this cleaning action will be continued as the spreaded or bat cotton passes upwardly of the drums 8' in connection with the cleaning screen 18 and over the cleaning screen 17 in connection with the drums 8.
- 40 This continued cleaning action upon the cotton results in the same being in a clean state when delivered to the upper stretch of the carry-off belt 9. This carry-off belt 9 may lead to a gin or other place of discharge.
- 45 In communication with the housing 1 through the top thereof and at a point substantially above the drums 8' is a hopper 26 into which the separator S may be arranged to discharge should it be desired to 50 omit the operation of the cotton being carried along over the top of the drums 8.

From the foregoing description it is thought to be obvious that a cotton cleaner constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation

of the several parts herein shown in carrying out my invention in practice except as hereinafter claimed.

I claim:

1. A cotton cleaner comprising, in combination, a housing, a substantially horizontally disposed series of spiked drums within the housing arranged side by side, a second series of drums arranged side by side, said second series being in vertical relation to the first series, a cleaning screen underlying the first series of spiked drums and extending along the opposite sides of the second series, and means for delivering cotton to the first series of drums. 70
2. A cotton cleaner comprising, in combination, a housing, a series of spiked drums within the housing arranged side by side, a second series of drums arranged side by side, said second series being in angular relation to the first series, a cleaning screen underlying the first series of spiked drums and extending along the opposite sides of the second series, means for delivering cotton to the first series of drums, said second series of drums being in depending relation with respect to the first series, and a collecting hopper arranged below said second series of drums. 80
3. A cotton cleaner comprising, in combination, a housing, a series of spiked drums within the housing arranged side by side, a second series of drums arranged side by side, said second series being in angular relation to the first series, a cleaning screen underlying the first series of spiked drums and extending along the opposite sides of the second series, means for delivering cotton to the first series of drums, said second series of drums being in depending relation with respect to the first series, a collecting hopper arranged below said second series of drums, and a collecting hopper underlying the first series of drums and discharging into the first hopper. 90
4. A cotton cleaner comprising, in combination, a housing, a substantially horizontally disposed series of spiked drums within the housing arranged side by side, a second series of drums arranged side by side, said second series being in vertical relation to the first series, a cleaning screen underlying the first series of spiked drums and extending along the opposite sides of the second series, means for delivering cotton to the first series of drums, a conveyor arranged adjacent to the first series of drums, and means for directing cotton either to the drums or to the conveyor. 100

In testimony whereof I hereunto affix my signature.

JOHN M. STUART.
